UNITED STATES PATENT OFFICE.

JOHN C. GLAS, OF LAKE VIEW, NEW YORK.

DESIGN FOR A SNAP-GAGE.

SPECIFICATION forming part of Design No. 30,625, dated April 25, 1899.

Application filed March 30, 1899. Serial No. 711,075. Term of patent 7 years.

To all whom it may concern:

Be it known that I, JOHN C. GLAS, a citizen of the United States, residing at Lake View, in the county of Erie and State of New York, 5 have invented and produced a new and useful Design for a Snap-Gage, of which the following is a specification.

This invention is a new and useful design for a snap-gage, the essential features residing in the peculiar shape and construction of the device as a whole, which will be fully described hereinafter.

In the drawings forming part of this specification, Figure 1 is a perspective view of a 5 snap-gage constructed in accordance with my invention. Fig. 2 is a side view of the same. Fig. 3 is an end view.

Referring particularly to the drawings, A indicates the shank or handle portion, having 10 the parallel straight sides A' and the curved end A². Curved arms B extend from the

shank or handle portions A, the inner faces of said arms being straight and parallel, as shown at B', and having gage-teeth C arranged thereon. To the rear of these teeth the arms 25 and the shank portion are curved out, as shown at D.

A snap-gage constructed as herein described can be readily fitted upon threaded work to gage the same, the straight portions of the 30 arms in advance of the gage-teeth acting as a guide for the purpose of enabling the threads to properly enter the gage.

Having thus fully described my invention, what I claim as new, and desire to secure by 35 Letters Patent of the United States, is—

The design for a snap-gage, substantially as herein set forth.

JOHN C. GLAS.
